UNITED STATES PATENT OFFICE.

PIOTR WARMINSKI, OF BALTIMORE, MARYLAND.

AEROPLANE CONTROL.

1,422,503.

Specification of Letters Patent. Patented July 11, 1922.

Application filed December 22, 1921. Serial No. 524,054.

To all whom it may concern:

Be it known that I, PIOTR WARMINSKI, a citizen of Poland, residing at Baltimore, in the county of Baltimore City and State of Maryland, have invented certain new and useful Improvements in Aeroplane Controls, of which the following is a specification.

This invention relates to certain new and useful improvements in controlling devices 10 for aeroplanes, and has particular reference to the idea of controlling the flow of gasoline or motive fluid to the engine of an aeroplane whereby the mechanism associated with the flow of motive fluid may be set at the point 15 to cause the aeroplane to stop in its flight after traveling a certain distance.

The invention being especially designed 20 for use in connection with bombing machines or explosive devices may be associated with aeroplanes of any size or proportion, it being intended, as an illustration, to construct comparatively small machines 25 to be carried by larger ones and also capable of attachment to obsolete aeroplanes, or aeroplanes intended for scrapping.

A further object of the invention is to 30 provide a controlling device for aeroplanes wherein a spring motor associated with a train of gearing is adapted for the shifting of an arm to shut off the supply of motive 35 fluid to the gas engine of the aeroplane, the movable arm for controlling the supply of the motive fluid being initially set in various positions to vary the length of travel of the 40 aeroplane for the motive supply before the fluid supply to the motor is shut off, the aeroplane carrying an explosive or other destructive matter to be released when the aeroplane alights.

With the above general objects in view 45 and others that will appear as the nature of the invention is better understood, the same consists of the novel form, combination and arrangement of parts hereinafter more fully described, shown in the accompanying drawing and claimed.

In the drawing, wherein like reference 50 characters designate corresponding parts throughout the several views,

Figure 1 is a side elevational view, partly broken away of an aeroplane showing the present invention operatively associated therewith,

Figure 2 is a vertical sectional view of the 55 housing containing the spring motor

mechanism for controlling the supply of motive fluid or gasoline to the aeroplane engine, showing the vertically movable arm supported on the rotatable screw shaft for operating the tensioned valve to stop the 60 feed of the gasoline,

Figure 3 is a horizontal sectional view taken on line III—III of Fig. 2 showing the train of gearing of the spring motor.

Figure 4 is a detail sectional view taken 65 on line IV—IV of Fig. 2 showing the gearing train operating the screw shaft for moving the valve actuating arm,

Figure 5 is a detail sectional view taken 70 on line V—V of Fig. 2 showing the hinged slotted guide for the valve actuating arm,

Figure 6 is a detail sectional view taken 75 on line VI—VI of Fig. 2 showing the screw pin connection between the hinged slotted guide for the valve actuating arm and a bracket,

Figure 7 is a detail sectional view taken 80 on line VII—VII of Fig. 2 showing the valve actuating arm working in the slotted guide with the outer end of the arm overlying the upper end of the valve stem for controlling the fuel supply, and

Figure 8 is a detail sectional view taken 85 on line VIII—VIII of Fig. 2 showing the fuel supply pipe and the controlling valve associated therewith.

Referring more in detail to the accompanying drawing and particularly to Fig. 1 there is illustrated an aeroplane of ordinary construction embodying a fuselage 1 having 90 the usual steering empennage 2, the same being supported on ground wheels 3 and having a forwardly positioned propeller 4 operated by the motor 5, the forward end of the fuselage being provided with a bearing block or mounting 6 for said motor. The fuel supply for the motor includes a gasoline tank 7 having pipe lines 8 and 9 leading to the motor while controlling mechanism for regulating the supply of fuel to the motor 95 is arranged within the casing 10 having a side door opening 11 and through which the pipe sections 8 and 9 extend.

The controlling means for the fuel supply 105 embodies a spring motor mechanism including a train of gearing and a screw shaft supporting an arm that actuates a valve in the fuel supply pipe, there being illustrated a bracket plate 12 secured to one side wall of the casing 10 and having spaced inwardly 110

directed arms 13, 14 and 15. A perpendicular shaft 16 having a key portion at its upper end is journaled in the outer end of the arm 13 and carries a gear 17, a coil band 5 spring 18 surrounding the shaft 16 and secured thereto at its inner end as at 19 while the outer end of the spring is secured as at 20 to the adjacent wall of the casing 10.

A train of gearing is associated with the 10 power gear 17, the same including a gear 21 journaled on the arm 14 and having fixed thereto a pinion 22 in mesh with a gear 23 journaled on the bracket arm 15, the gear 23 carrying a pinion 24 as clearly 15 shown in Fig. 3.

The opposite wall of the casing 10 supports a bracket plate 25 carrying inwardly directed arms 26, 27, 28, and 29', the arm 27 supporting a relatively large gear wheel 20 29 that meshes with the pinion 24 associated with the gear wheel 23. A pinion 30 carried by the gear 29 meshes with the gear 31 journaled on the arm 28 while the pinion 32 carried by the gear 31 meshes with the gear 25 33 journaled on the arm 29', said gear 33 being fixed to the upper end of the perpendicular screw shaft 34 shown more clearly in Figs. 2 and 4, and journaled at its lower end in the bearing 35 carried by the bottom wall 30 of the casing 10. A weighted governor is associated with the train of gearing, the same including the pinion 36 journaled on the outer end of the arm 26 and in mesh with the gear 29, said pinion 36 carrying a 35 weighted governor 37 as clearly shown in Figs. 2, 3 and 4.

A perpendicular slotted guide 38 is hinged at its lower ends as at 39 to the bottom wall of the casing 10 and has the 40 upper end thereof detachably secured by the screw 40 to the outer end of the arm 29' as shown in Figs. 2 and 6. A valve actuating arm 41 having an operating end 42 freely extends through the slotted guide 45 38 and has the inner end 43 thereof threaded onto the screw shaft 34. The liquid fuel in the tank 7 passing through the pipe sections 8 and 9 is valve controlled, the pipe sections 8 and 9, as shown in Fig. 2 entering 50 a valve block 44 with the passage through the block controlled by the valve 45 tensioned as at 46 and carrying an upwardly projecting stem 47 that is vertically aligned with the operating end 42 of the 55 valve actuating arm 41.

In the operation of the device, it being desired to cause the aeroplane to travel a certain distance and then have the fuel supply shut off, the slotted guide 38 is disengaged from the bracket arm 29' and moved outwardly as indicated by the arrow line in Fig. 2 to permit perpendicular adjustment of the valve actuating arm 41 upon the screw shaft 34. The slotted guide is then 60 65 returned to the position shown in Fig. 2

and secured by the thumb screw 40. In placing the spring 18 under tension, the sliding hand catch 17^a shown in Figs. 2 and 3 is disengaged from the gear 17 and a key applied to the upper end of the shaft 16 70 will cause a rotation of the shaft to place the spring under tension, movement of the gear 17 being controlled by the hand operated catch 17^a, and with the valve actuating arm 41 spaced from the valve stem 47, 75 the flow of motive fluid to the tank 7 from the motor 5 is unobstructed. The catch 17^a is then disengaged from the gear 17 and the spring motor 18 functions to rotate the train 80 of gearing, the speed of rotation being balanced by the governor 37, while said gearing train rotates the screw shaft 34. The valve actuating arm 41 threaded on the screw shaft 34 being prevented from rotary movement by freely extending through the 85 slotted guide 38 is caused to move downwardly in a direction toward the valve stem 47, and when the aeroplane has traveled the distance for which the same was primarily set, the operating end 42 of the valve 90 actuating arm engages the valve stem 37 to close the valve 45 in the valve block 40 and accordingly shut off the supply of liquid fuel from the pipe section 8 to the pipe section 9 thereby causing the stopping of the 95 motor 5 and the collapse or descent of the entire aeroplane. The threaded ratio on the screw shaft 34 is so correlated with the tension of the spring motor 18 that the definite positioning of the actuating arm 41 100 upon the screw shaft will greatly determine the length of travel of the aeroplane before the stopping of the motor 5. The device is designed for carrying explosives or projectiles into the lines of the enemy and 105 may also be employed for practice and destruction work in the scrapping of obsolete aeroplanes, the same being extremely simple in construction and operation and readily adaptable to aeroplanes of all types of 110 manufacture.

What is claimed as new is:—

1. Means for controlling the flow of fluid comprising a fluid pipe, a controlling valve therefor, motor operated means to stop the 115 flow of fluid including a gearing train, a screw shaft rotated thereby, a valve actuating arm threaded on said shaft rotated thereby, a valve actuating arm threaded on said shaft adapted to be moved into engagement with the valve, and a slotted guide for the valve actuating arm to prevent rotary movement of the arm relative to the screw shaft, said slotted guide being movable relative to said arm to permit the arm to be 120 moved relative to the screw shaft whereby the same may be initially set in the desired position on the screw shaft.

2. Means for controlling the supply of liquid fuel to an aeroplane motor comprising 130

ing in combination with a pipe line having a controlling valve therein, motor mechanism associated with said valve adapted to be moved into engagement therewith for stopping the flow of fuel to the motor, said motor mechanism including a spring driven gear train, a screw shaft rotated by said

train, a slotted guide positioned parallel with the screw shaft and a valve actuating arm threaded on the screw shaft and adapted to be moved into engagement with the valve.

In testimony whereof I affix my signature.

PIOTR WARMINSKI.
